UNITED STATES PATENT OFFICE.

SAMUEL ANGROVE, OF PROVIDENCE, RHODE ISLAND, ASSIGNOR, BY MESNE ASSIGNMENTS, TO BURNOYL HEATING CORPORATION, OF PROVIDENCE, RHODE ISLAND, A CORPORATION OF RHODE ISLAND.

NOZZLE FOR LIQUID-FUEL BURNERS.

Application filed August 25, 1926. Serial No. 131,379.

This invention relates to an apparatus for burning fuel such as hydrocarbon oils; and has for its object to provide an oil discharge nozzle which is so constructed that it will 5 cause the oil to be better picked up by the air passing over it to increase the combustion of the oil.

A further object of the invention is to corrugate the inner bottom surface of the 10 nozzle so as to break up the oil and expose a greater surface thereof to the air passing through the nozzle.

A still further object of the invention is to provide an oil nozzle of such shape relative to the air passage for the draft that the air will pass through the nozzle as well as about the outside thereof to prevent overheating of the nozzle.

With these and other objects in view, the 20 invention consists of certain novel features of construction, as will be more fully described, and particularly pointed out in the appended claims.

In the accompanying drawings:

25 Figure 1 is a side elevation of the oil burning apparatus showing its location relative to the furnace.

Figure 2 is a sectional elevation of the fire pot and nozzle and the portion of the air 30 draft supply pipe.

Figure 3 is a sectional end elevation on line 3—3 of Figure 2.

Figure 4 is a perspective view of the nozzle.

35 Figure 5 is a longitudinal sectional view through the nozzle.

Figure 6 is a perspective view of a modified form of nozzle.

It is found in the practical operation of 40 liquid fuel burners of the character adapted to heat residences and dwelling houses, of advantage to provide an oil distributing nozzle which will not burn out due to overheating and one which will break up and expose 45 the maximum surface of the oil to the draft of air passing through the nozzle over the oil; and I have provided a nozzle which is of a shape different from that of the air supply pipe and corrugated on the inner 50 lower surface of the nozzle, whereby air may pass about the nozzle to keep it cool and the air passing through the nozzle will pass over the oil trickling along the corrugated surface to better pick up the oil and carry it

to the firepot to be burned; and the following is a detailed description of the present embodiment of the invention showing one construction by which these advantageous results may be accomplished:—

With reference to the drawings, 10 designates the front wall of a furnace in which is located a hydrocarbon burner having a firepot 11 with an air draft supply 12 and motor driven fan 13. The oil is supplied from any suitable source by gravity through pipe 14 and valve 15 and is discharged into the nozzle 16 which is illustrated as of triangular shape and has a three point bearing support 17, 18 and 19 in the air supply boss 20.

The nozzle 16 is provided at its intake end with projections 21 on the outer surface which raises this end from the draft boss 20 to cause the nozzle to be inclined slightly with its discharge end 22 lowermost. The 75 nozzle is held in its desired position by means of a positioning pin 23 extending into an opening 24 in the nozzle.

The inner surface of the nozzle 16 is provided with a shallow oil well 25 at its oil receiving end, and is corrugated as at 26 providing a series of inclined surfaces 27 over which the oil must pass in discharging from the nozzle.

The air draft entering through the nozzle 85 in the direction of the arrow 28 picks up the oil and carries it into the firepot 11 to be burned.

It will be noticed in Figure 3 that the cross 90 sectional area 29 of the nozzle is as great as the aggregate cross-sectional areas of the remaining portions 30 about the outside of the nozzle, and the air passing about the nozzle in this way keeps the same sufficiently cool to prevent the same from being destroyed by the heat.

In Figure 6 the nozzle 31 is illustrated of rectangular shape to fit within the circular draft supply pipe 21, it being understood that any suitable shape different from that 100 of the air supply pipe may be provided to permit the air to circulate about the nozzle walls as well as through the same.

I have also illustrated in this application 105 a novel form of fire pot which forms the subject of another application filed August 25, 1926, Serial No. 131,379.

From the foregoing, it will be seen that I

have provided a nozzle of a simple construction which is such that the oil is broken up to increase the surface exposed to the air draft and yet one which is so shaped and positioned in the air draft as to prevent the same from being overheated and destroyed.

The foregoing description is directed solely towards the construction illustrated, but I desire it to be understood that I reserve the privilege of resorting to all the mechanical changes to which the device is susceptible, the invention being defined and limited only by the terms of the appended claims.

13 I claim:

1. In an oil burner, an oil supply conduit, a tubular discharge nozzle open at its ends and positioned in the air draft and having a shallow well for receiving a substantial quantity of the oil, and a transversely corrugated surface adjacent its discharge end

over which the oil passes from said well in discharging to increase its surface exposed to the air draft, the corrugations of said surface extending entirely across said nozzle. 25

2. In an oil burner, a cylindrical air supply conduit, and an oil discharge nozzle open at both ends and polygonal in cross-section resting therein and contacting at its edges with the interior of the conduit at a plurality of points transversely thereof, whereby air may pass through and about said nozzle. 30

3. In an oil burner, a cylindrical air supply conduit, and an oil discharge nozzle open at both ends and substantially triangular in cross-section resting therein and contacting with the interior of the conduit at a plurality of its edges, whereby air may pass through and about said nozzle. 35

In testimony whereof I affix my signature.

SAMUEL ANGROVE.
